Wood and Company Limited, Toronto, Ontario,
Canada

Application June 7, 1951, Serial No. 15,454

Term of patent 3½ years

(Cl. D59—2)

To all whom it may concern:

Be it known that we, Geoffrey H. Wood and Robert Mulholland, both citizens of Canada, and residents of Toronto, Canada, have invented a new, original, and ornamental Design for Place Mats, of which the following is a specification, reference being had to the accompanying drawing, forming a part thereof.

The figure is a plan view of a place mat, showing our new design. The right-hand side of the place mat has been partially omitted for convenience in illustration.

We claim:

The ornamental design for a place mat, as shown and described.

GEOFFREY H. WOOD.
ROBERT MULHOLLAND.
